UNITED STATES PATENT OFFICE.

JOSEPH H. TUTTLE, OF WEST SOMERVILLE, MASSACHUSETTS, ASSIGNOR TO
CLARENCE B. FROST, OF CAMBRIDGE, MASSACHUSETTS.

PACKAGE-SEALING APPARATUS.

No. 848,706.

Specification of Letters Patent.

Patented April 2, 1907.

Application filed January 11, 1907. Serial No. 351,847.

To all whom it may concern:

Be it known that I, JOSEPH H. TUTTLE, of West Somerville, in the county of Middlesex and State of Massachusetts, have invented 5 certain new and useful Improvements in Package-Sealing Apparatus, of which the following is a specification.

This invention relates to package-sealing apparatus.

10 The object of the invention is to provide improved means for directing a strip of binding-tape to a device for rendering the tape adhesive and thence to the package which is to be sealed, including improved means for 15 severing the part which is used on the package from the strip and for retaining the tab end of the strip projecting in a position convenient for use with the next package, but 20 out of contact with the device for rendering it adhesive.

To this end the invention comprises two surfaces spring - pressed together, between which the tape passes, arranged at such an angle and position that the tape on issuing 25 therefrom is projected over a device for rendering it adhesive. On the farther side of the device the tape passes under a guide-pin and through a swinging carriage, which holds each side of the tape with a light grip, 30 allows a slight forward-and-backward movement thereof, and at the same time readily permits the removal of the tape from the carriage by the operator to render the tab end adhesive. The severing-knife is placed above 35 and beyond the carriage and is mounted pivotally, so that when not in use the knife recedes on being touched, but is rendered firm and operative when the tape is to be severed; owing to engagement of a tailpiece on the 40 knife with a rear part of the strip of tape.

The plates which project the tape are curved, giving an arch shape to the tape, thus stiffening it and assisting in preventing its contact with the device for rendering it adhesive except when it is drawn into contact therewith by superior force in the act of drawing the tape from the apparatus.

50 The details of the foregoing and of other parts of the invention are set forth hereinafter, reference being had to the accompanying drawings, in which—

Figure 1 represents a side view of the apparatus embodying the invention, partly in section. Fig. 2 is a plan view of part of the

apparatus. Fig. 3 is a front view of the 55 same. Fig. 4 is a cross-section showing the form assumed by the tape at the point 44 of Fig. 1 after passing through the projecting device. Fig. 5 represents another detail viewed approximately in the direction of 60 line of travel of the tape.

Referring to the drawings, 10 represents a frame in which is supported a device for rendering tape adhesive. As here represented this consists of a water-pan 11, into which a 65 wheel 12 dips, the surface of the wheel being covered with an absorbent material, so that moisture rises either by rotation of the wheel or by capillary attraction and maintains the top surface thereof moist. The water-pan 70 is replenished from a closed reservoir 13, which has a neck 14 terminating below the surface of the pan. Whenever the level of water in the pan falls below the orifice of the neck 14, a little air enters and a corresponding amount of water escapes into the pan 11 until the level of water is raised and the orifice sealed thereby.

75 It is contemplated that with this device tape will be employed in which a coating of 80 gum or mucilaginous material has been applied to one surface of the tape and dried thereon, requiring only the addition of moisture to make it adhesive; but it is obvious that the pan might contain mucilage instead 85 of water or that another form of device for rendering the tape adhesive might be substituted. The tape is marked 15 and when being drawn forth passes under guide-pin 16, through directing and arch-forming plates 17 90 18, over moistening-wheel 12, under guide-pin 19, through carriage 20, and thence out from the apparatus. The supply of tape may be drawn from any convenient source. The plates 17 18 are preferably curved in a 95 direction transverse to the line of travel of the tape, as clearly shown in Figs. 2, 5. A convenient method of supporting the arch-projecting plates 17 18 is represented in Fig. 5, in which the plate 18 is shown supported, 100 by a shank 24, which is fastened by screw 21 to a support rising from the back side of the water-pan. The shank of the top plate 17 has a tang 22, which passes through a slot in the shank 24 and is adjustable with respect 105 to the under plate by a screw 23, being made of spring metal. The plate 17 is arched in form, and the proximity of the plates 17 and

18 is to be adjusted by the screw, according to the degree of arch desired to be imparted to the tape. The angle at which these plates project the tape may be adjusted about the 5 screw 21 as a pivot. Normally when not in use the tape is by this device pointed upward, as indicated by the dotted lines in Fig. 1, and the arch form of the tape gives stiffness to the tape, so that it does not bend downward 10 and fall into contact with the moistening-wheel 12, but passes over the same, bearing upward against the external guide-pin 19.

Guide-pin 19 is so located that the straight line between its under surface and the direct- 15 ing-plates intersects the moistening-wheel, so that when the tape is drawn taut, as in withdrawing tape from the apparatus, the tendency of the tape to assume a straight line inevitably brings it against the moistening- 20 wheel, as shown by the full lines 15 in Fig. 1.

A tab-carriage of peculiar form (shown best in Fig. 3) constitutes another feature of the invention. As here illustrated the carriage consists of a piece of wire hung from 25 pins 25 on top of the guide-pin 19 and capable of a slight to-and-fro swinging motion in a direction of travel of the tape. The wire comprises side uprights 26, close under the guide-pin, inclined shelves 27, next thereunder, and an outward bend 28 below that, so that the lower portions 29 fall outside the width of the moistening-wheel. While the 30 shape and arrangement of these parts may be varied in many ways, the form here illustrated shows the main features of this portion of the invention, the features thus described being duplicated on each side of the medial line of the tape. The space between the parts 26 is preferably the precise width of 35 the tape, although the device will work if it be a little less or a little more. The parts 27 are designed to project under the tape a little, enough to support it, except when the tape is removed by superior force, and the angle between parts 28 and 29 is so located that when 40 sprung backward its contact with the moistening-wheel, as shown in Figs. 3 and 1, forms the rearward limit of swing of the wire. The swing of this carriage need be but slight. 45 When the tape is withdrawn from the apparatus, it is normally in contact with the under side of the pin 19, and its incidental contact with the closely-adjacent upright portion 26 of the carriage draws the carriage forward. When the tab end is released by severing the tape, as hereinafter described, the 50 forward draft ceases and the tape tends to assume the dotted position shown in Fig. 1. The rising of the portion 30 of the tape from 55 the full-line position to the dotted-line position 30' requires withdrawal of the tab end slightly into the apparatus, and the carriage 60 swings inward to permit this.

It should be understood that when the 65 tape has been severed the elasticity and stiff-

ness of the tape will generally hold it against the under side of guide-pin 19; but if an elastic tape be used or under some conditions of weather there is a tendency of the tab end to sag, and when this happens the 70 tape is supported upon the side shelves 27 and frequently slightly adheres thereto; but the movability of the carriage permits carriage and tape to swing inward together, and thus permit the point 30 to rise to position 75 30', whereas if the carriage were not movable the adhesion might be sufficient to prevent the point 30 from rising out of contact with the moistening-wheel. Under conditions of ordinary use the tab end retains its moisture 80 sufficient for adhesion from the point 30 to the end of the projecting tip 15'; but if the end becomes dry the operator may with his hand remove the tape from the shelves by pulling the same downward, when the tape 85 will bend a little at each edge and pass below, and he can then touch the same to the moistening-wheel below, and upon raising it again the portions 28 will guide it back to its normal situation. 90

When the tape is to be severed, the operator, holding it or a package to which it is attached, raises it toward the severing-blade 31. The arrangement and mounting of this 95 constitute another feature of the invention, the blade having a shank 32 and a pivotal support close to the blade between it and the shank. When the tape is raised into contact with the blade the blade tends to recede, swinging around the pivot 33. This throws 100 the shank 32 forward into contact with the portion of the tape near the guide-pin 19, which stops its forward movement, and thus stops recession of the blade 31, so that the 105 blade pierces and severs the tape, after which the tab end falls back to the position 15'. If a person accidentally touches the blade except as above described, the blade swings backward about its pivot 33, receding from the touch, and thus doing no harm to the person. 110 In case of accidental contact of a person with the projecting tab end which might push the same back into the apparatus out of reach such effect is prevented by the friction of the side portions 26 or 27 of the carriage 115 upon the tab and also by the transverse arch back of the point 30', which enables the plates 17 18 to hold the tape stiff against backward pressure. The plates 17 18 also furnish a tension which maintains the forward part of the tape always in proper relation to the moistening device and at the same time eliminates the necessity of a tension device upon the supply-roll or upon the entrance of the tape to the apparatus. The 120 tension is increased by adjusting these plates nearer together, which also makes the arch of sharper curvature and causes the arch to extend farther over the moistening device before the paper reassumes its natural flat 125 130

shape. This enables very thin tape and tape having but little stiffness to be used. The adjustment can be varied according to the kind of tape in use. The arch-forming plates are not necessarily of the precise form shown, and particularly the plate 18 does not need to be as broad as here shown, the arch effect being produced by a member, such as 18, pressing the middle of one side of the tape in one direction and a member or members, such as 17, pressing the edges of the other side of the tape in the opposite direction. It will also be noted that the arch may be inverted from the form here shown with like effect. If the arch-forming feature be omitted, a higher degree of stiffness and elasticity of the tape is required, and the directing-plates should then have a sufficient number of points arranged in parallelism in the direction the tape is traveling to project it definitely in the desired direction.

Another advantage of the arch formation is that in case a drop of water runs backward down the tape from the high point 30' it seeks the lowest path and passes the guide-plates 17 18 without touching them or moistening any part of the gummed tape which is in contact therewith, thus avoiding adhesion of the tape thereto. This is because the guide-plates 17-18 are preferably so arranged that the guide-bearing on the under side of the tape makes contact only with the higher portions of such under side. As represented in the drawings, the plate 18 contacts against the top of the arch, while any drop of water running down seeks a path along the base of the arch.

The severing apparatus here shown is an improvement upon the devices for a similar purpose heretofore proposed in that it is here proposed to mount the blade in its operative position, which may be exposed to accidental contact with the person.

I claim—

45 1. A device for rendering tape adhesive, in combination with means for arching the tape transversely and directing the same over said device.

50 2. A device for rendering tape adhesive, in combination with guides pressing the edges and the center of the tape in opposite directions, forming a transverse arch in the tape, and directing the tape over said device.

55 3. A device for rendering tape adhesive, in combination with means directing the tape

upward over said device, forming it into a shape of uneven levels transversely and supporting its under side only at the upper levels thereof.

4. A device for rendering tape adhesive, in combination with plates set substantially parallel to each other, engaging opposite sides of the tape and directing it thereover, and means to adjust the distance between the plates between which the tape passes. 60

5. A device for rendering tape adhesive, in combination with plates set substantially parallel to each other, engaging opposite sides of the tape and directing it thereover, there being a mutually-opposing spring and screw 70 for adjusting the one plate with respect to the other.

6. A device for rendering tape adhesive, in combination with a carriage on the delivery side thereof, movable fore and aft and engaging the tape edgewise. 75

7. A device for rendering tape adhesive, in combination with a support adjacent to the delivery side of the device, comprising side shelves supporting the edges of the projecting tape; there being a space free of support for tape between the shelves. 80

8. A device for rendering tape adhesive, in combination with a support adjacent to the delivery side of the device, comprising side shelves supporting the edges of the projecting tape out of contact with said device, the space between the shelves being free of support for tape, and there being side guides between said device and the inner edges of said 90 shelves.

9. A severing device for tape, comprising a guide for the tape; a lever, having at one end a portion adapted to be engaged by tape proceeding from the guide; a fulcrum, and a severing-blade at its other end, beyond the fulcrum, normally projecting in operative position, the first end being approximately in line between it and said guide and thus giving leverage against the tape to hold the blade 100 against recession when the tape is being severed. 95

In testimony whereof I hereto affix my signature, in presence of two witnesses, at Boston, January 9, 1907.
